W. E. WINE

CAR DOOR LOCKING MECHANISM

Original Filed June 23, 1921

UNITED STATES PATENT OFFICE.

WILLIAM E. WINE, OF TOLEDO, OHIO.

CAR-DOOR-LOCKING MECHANISM.

Original application filed June 23, 1921, Serial No. 479,723, now Patent No. 1,460,009, dated June 26, 1923.
 Divided and this application filed December 20, 1922. Serial No. 607,965.

To all whom it may concern:

Be it known that WILLIAM E. WINE, a citizen of the United States of America, residing at Toledo, in the county of Lucas, and State of Ohio, has invented certain new and useful Improvements in Car-Door-Locking Mechanisms, of which the following is a specification.

My invention relates to new and useful improvements in car door locking mechanisms, and more especially to a supporting and locking mechanism for the drop doors of freight cars, the present application being a division of my former application bearing Serial No. 479,723, filed June 23, 1921, now Patent No. 1,460,009, granted June 26, 1923.

One of the principal objects of the present invention is to provide a supporting and locking mechanism for drop bottom doors of freight cars wherein the locking mechanism consists primarily of a bracket, an outer plate, a hook pivotally supported between the bracket and outer plate, retaining means also pivotally supported between the bracket and the plate for holding the hook in its locked position, and means for securing the supporting mechanism to the car body.

With these and other objects in view, the invention consists in certain new and novel constructions and combination of parts as will be hereinafter more fully described and pointed out in the claims.

Referring now to the drawings showing a preferred embodiment of the invention.

Fig. 1 is a fragmentary portion of a side of a car and a portion of a door, and a locking mechanism, the latter being shown in its operated position.

Fig. 2 is a transverse sectional view taken through a portion of the car and through the drop door, the locking mechanism being shown in elevation.

Referring now more in detail to the drawings, a fragmentary portion of a side of a car 1 is shown, and a fragmentary portion of a side sill 2, the same being shown as being formed of a structural steel channel with the back of the same substantially in line with the inside face of the inside of the car, the web being vertical and the horizontal flanges located beneath the bottom edge of the side planking and outstanding from the

center of the car. A portion of a center sill 3 is shown as consisting of the ordinary plate and channel type, and on the plate of which is shown a portion of the floor planking 4. There are provided brackets 5 (one only being shown) to which is hinged a drop door 6, which is arranged to extend from the center sill construction to the side of the car and to swing about an axis to the center sill of the car, thereby providing for the discharge of the lading along side of the track.

The door may be of any preferred construction, and in the present instance, is shown of door planks supported upon battens. A reinforcing hinge strap 9 passes beneath the planking and extends inwardly to the pivoted or hinged edge of the door where it may be formed in loop fashion as at 10 to provide the door portion of the hinge.

At the outer or free edge of the door, this reinforcing hinge strap 9 extends slightly outside of the line of the car side and there formed again in loop fashion as at 11, to provide an accessible extension or handhold for lifting the door and to further provide a locking face or seat for the engagement of the door supporting hook to be hereinafter mentioned, when the door is in its closed position. It will be understood that a plurality of these members may be provided for each door and a plurality of hooks may be used so the door may be properly supported throughout its free edge.

Referring now to the locking and supporting mechanism, a hook member such as 12 is pivoted on the side sill for each of the members 9 to engage the loop ends 11, and is arranged to swing longitudinally of the car or at right angles to the swing of the door about a pivotal point 13 just outside and along the edge of the channel 2. A bracket, such as 14, is provided for each hook 12 and extends back into the cavity of the channel so as to bridge the otherwise open space between the web and edges of the flanges. This bracket 14 is riveted to the web of the channel 2, to simplify the problem of removal for repairs. A hook retaining cam or dog 15 is pivoted as at 16 to the bracket 14 to prevent the accidental release of the hook 12. When this cam or dog is rotated about its pivot 16 in one direction, it allows the hook 12 to be driven out of

position beneath the loop portion 11 of the hinge member 9 secured to the bottom of the door, thus allowing the door to drop. When this hook is in position beneath the projection 11 for supporting the door, the dog 15 may be rotated in the proper direction to engage the back of the hook and hold it and the door in their locked position. An outer or retaining plate 17 may be applied over the hook 12 and cam 15 of each bracket, the rivets coincident with the pivot points 13 and 16 as well as an additional rivet 18 passing through this plate and through the bracket and the channel 2, thereby economically tying all of these parts together and producing a compact arrangement and one especially suited to the rough service, to which the same will be subjected. The bracket 14 may also have integrally formed spacing lugs 19 formed at the rear thereof to form spacers between the channel and the main plate of the bracket.

It is to be noted that the door falls approximately on a line with the outer edge of the flange of the channel 2, the extension 11 lying outside of the lines of the door and outside of the lines of the channel 2. The hook 12 also lies outside of the lines of the door and outside of the lines of the channel 2 but within the lines of the projection 11, thereby allowing free movement of the hook and free movement of the door excepting when the hook is in the projection 11. This permits the maximum of the door opening, and it will be seen that the door is also supported from the two sill members, namely the center sill and the side sill.

It will also be seen that the locking and supporting mechanism may be applied as a unitary structure to the side sills of freight cars, and necessitating the drilling of but

three holes in the side sill when the locking mechanism is applied.

Seats to be engaged by the hooks other than the form shown by the projection 11 may be used if so desired.

From the foregoing it will be seen that I have designed a locking and supporting mechanism which may be applied as a unit; which is relatively cheap to manufacture, and which may be quickly operated, it simply being necessary to throw the dog in one direction and force the hook from its seat, while to support and lock the door, it is only necessary to force the door to a closed position and, after the hook has engaged the seat, the dog will then be thrown to tightly jam and lock the hook in this locked position.

Many slight changes might be made without in any way departing from the spirit and scope of the invention.

Having thus described my invention, what I claim as new and desire to secure by Letters Patent is:—

In a door device for railway cars, the combination with a car framing including side and center sills, the former having an outwardly directed flange, of a door hingedly connected to said center sill, a portion of said door being adapted to underlie the flange of said side sill, a hook for holding said door in closed position, and a bracket member for pivotally supporting said hook, said member including a plate having an offset portion engaging the web of said sill thereby to space the plane of movement of said hook clear of said flange.

In testimony whereof I affix my signature.

WILLIAM E. WINE.
